(57) **CLAIM**

The ornamental design for a cold neck wrap, as shown and described.

DESCRIPTION

FIG. 1 is a front perspective of a cold neck wrap showing my new design;

FIG. 2 is a front elevation thereof;

FIG. 3 is a left side elevation view thereof;

FIG. 4 is a right side elevation thereof;

FIG. 5 is a rear elevation view thereof;

FIG. 6 is a rear elevation view thereof, in an open position;

FIG. 7 is a front elevation view thereof, in an open position;

FIG. 8 is a detail fragmentary view thereof, in an open position

FIG. 9 is a detail fragmentary view thereof, in an open position;

FIG. 10 is a top plan view thereof, in a closed position;

FIG. 11 is a top plan view thereof, in an open position; and,

FIG. 12 is a bottom plan view thereof.

FIGS. 11 and 12 have been shown broken away to show indeterminate length.

The evenly spaced broken lines shown in FIGS. 6 and 7 represent claimed stitching. All of the other broken lines shown in FIG. 9 represent environmental subject matter that forms no part of the claimed design.
